UNITED STATES PATENT OFFICE

CULLEN L. HUNTOON, OF LOS ANGELES, CALIFORNIA

RUBBER BAND CUSHION SHOE SOLE PRESS

Application filed July 12, 1928. Serial No. 292,225.

This invention relates to improvements of a device for applying shoe soles to footwear and may be considered as an improvement over the device disclosed in my prior Patent 5 Number 1,634,996, issued July 5th, 1927.

An object of the invention is to provide a form of screw press, having an elastic or resilient bed adapted to be brought into engagement with a shoe sole to cause pressure to be exerted against the shoe sole while the cement employed in fastening the sole to the upper is drying.

Another object of the invention is to provide a form of screw press adapted to be used in conjunction with the band press disclosed in my prior patent, for increasing the amount of pressure exerted against the shoe sole by the bands of the band press.

A further object of the invention is to provide a screw press having a resilient bed, which is of simple and durable construction, and in which the parts adapted to become worn, or to lose their efficiency in the course of time, may be easily and quickly replaced.

With the foregoing and other objects, which will be made manifest in the following detailed description and specifically pointed out in the appended claims, reference is had to the accompanying drawings for an illustrative embodiment of the invention, wherein:

Figure 1 is a top plan view of the improved rubber band cushion shoe sole press.

Fig. 2 is a vertical section, taken substantially upon the line 2—2 upon Fig. 1, parts being shown in elevation.

Fig. 3 is a vertical section, taken substantially upon line 3—3 upon Fig. 2, parts being shown in elevation.

Referring to the accompanying drawings, wherein similar reference characters designate similar parts throughout, the device consists of a work holding device, generally designated as 10, consisting of base plate 11, on which there is a web 12. Adjacent to one end of web 12 there is a shank 13, preferably provided with lateral reinforcing ribs 14. The shank on its lower end is formed to provide a shoe last shape 15, on which a shoe S is adapted to be mounted. On the edge of

the web 12 there are formed a plurality of notches 16, which are wider on their inner ends than at their entrances. A corresponding number of elastic rubber bands 17 are positioned in the notches 16 and are adapted to be stretched over the shoe sole 18, which is to be applied to shoe S. Small metal plates, not shown, are disposed between the rubber bands 17 and the entrance to the notches, so that the bands when stretched will not be pulled through the notches. One or more notches or recesses 19 may be formed on the back of shank 13, and which are adapted to receive rubber bands which can also be stretched over the shoe sole 18.

When these rubber bands are stretched over the shoe sole 18, it will be understood that they will exert a pressure on the shoe sole, urging it against the upper, and against the shoe last shape 15. One end of the base plate 11 is provided with a screw clamp 20 for mounting or fastening the work holding device on a table, or suitable support, while the shoe S is being positioned thereon and the elastic bands 17 are being stretched and positioned.

The construction of the work holding device as above described is the same as that disclosed in my prior patent above referred to.

The construction of the press is as follows: The press consists of a rectangular bed frame, having longitudinal side bars 21, connected by end members 22, and intermediate cross member 23 connects the side bars intermediate with their ends. This bed frame is supported by legs 24, arranged at its corners. A yoke 25 is mounted on the bed frame thus provided and has its sides provided at their lower ends with horizontal supporting bars 26, having hooked ends 27, which receive flanges 28 at the corners of the bed frame. Screws 29 are threaded through the ends of the supporting bars 26 and are tightened into engagement with the flanges, so that the yoke 25 is removable, but firmly supported upon the bed frame. Two screws 30 and 31 extend through the top of the yoke 25 and have a threaded engagement therewith. These screws are provided at their upper

ends with hand wheels 32 and 33 respectively. They are provided at their lower ends with followers 34 and 35, which have swiveled connections with their respective screws.

Centrally of the yoke 25 and on the underside thereof there is formed an arm 36 and this arm, together with the opposed sides of the yoke 25, has guide ribs 37, which are receivable in notches or recesses in the ends of the followers 34 and 35, guiding the followers in a vertical movement without rotation. On the followers 34 and 35 there are indicating arrows 38, which point toward indicia 39 on the arm 36. A resilient or elastic bed is formed on the bed frame by a series of rubber bands 40, which are slipped over the ends of the bed frame and are positioned side by side on the longitudinal side bars 21. A similar set of flat rubber elastic bands 41 is stretched and slipped over the side bars of the frame and are positioned side by side on the end members of the bed frame over the bands 40. This second series of bands is positioned in place before the yoke 25 is mounted on the bed frame and as the positions of the supporting bars 26 intermediate their ends are spaced from the end members of the bed frame as shown in Fig. 1, these supporting bars 26 in no way interfere with either of the sets of bands. In the preferred form of construction additional bands 42, which are somewhat wider than the bands of either series, are positioned or stretched on the bed frame and extended transversely across it beneath screws 30 and 31. The operation of the device is as follows:

The work holding device 10 is first mounted in a position inverted from that shown in Fig. 2 on a table or support. The work, which is the shoe S, is then applied to the shoe last shape 15 and the shoe sole 18 is then applied with cement. The rubber bands 17 are then stretched and caused to assume the position shown in Fig. 2, exerting a pressure on the shoe sole, which is more or less evenly distributed. It is highly desirable to have the pressure much greater than that which can be exerted by the bands 17 in many instances and in such cases the work holding device is removed from the table by loosening the screw clamp 20 and positioned on the bed of the press as shown in Fig. 2, with the base plate 11 beneath a follower and the portion of the rubber bands 17 across the shoe sole resting on a band 42 on the bed frame. When in this position the hand wheel is rotated, forcing its follower downward into engagement with plate 11. This causes band 42 and bands 40 and 41 to be flexed downwardly, causing them to be stretched and to increase the pressure exerted on the shoe sole 18 by the bands 17. When in this position the indicating arrow 38 on the follower indicates approximately the pressure exerted by the elastic band on the shoe sole. The device is al-

lowed to remain in this position until the cement has become thoroughly dry or hard, firmly fastening the shoe sole 18 to the upper. By virtue of the fact that crossed series of elastic bands are employed on the bed frame, these bands will exert a uniform or evenly distributed pressure on the shoe sole. As the yoke 25 accommodates two screws 30 and 31 with their respective followers 34 and 35, two work holding devices 10 with their respective shoes may be simultaneously mounted thereon, so that both will be finished at the same time.

If during the course of time any of the bands on the bed frame should deteriorate or lose their elasticity they can be easily and quickly replaced on loosening the screws 29 and removing the yoke 25.

The cross bar 23 divides the bed frame into two rectangles, over which the upper portions of the bands 40 and 41 are arranged. In this manner the bed frame is divided into two parts, the elastic means on each part being operable to a certain extent independently of the other as shown on Fig. 3.

From the above described construction it will be appreciated that a new rubber band cushion sole press is provided which may employ as part of its construction the device disclosed in my prior patent. However, an equivalent work holding device may be substituted therefor if found desirable. Furthermore, a high pressure is capable of being uniformly distributed over the shoe sole 18, while the cement is hardening.

Various changes may be made within the details of construction without departing from the spirit of the invention, as defined by the appended claims.

I claim:

1. A device of the class described comprising a work holding device on which the work is adapted to be mounted, elastic means on the work holding device adapted to be stretched over the work, so as to exert a pressure thereon, and resilient means adapted to be brought into engagement with the elastic means for increasing the pressure exerted thereby on the work.

2. A device of the class described, comprising a work holding device on which work is adapted to be mounted, elastic means on the work holding device adapted to be stretched over the work, so as to exert pressure thereon, a frame, elastic means on the frame, and means for bringing the work holding device into a position wherein the elastic means on the frame will be caused to engage the elastic means on the work holding device, so as to become stretched thereby and thus to increase the pressure exerted upon the work by the elastic means on the work holding device.

3. A device of the class described, comprising means providing a resilient bed,

- means providing a yoke over the bed, a hand-screw threaded in the yoke, a follower swiveled to the hand screw, a work holding device for supporting the work between the bed 5 and the follower, and an elastic means on the work holding device, adapted to be stretched over the work to exert a pressure thereon.
4. A device of the class described, comprising a bed frame, a yoke mounted upon 10 the bed frame, means upon the yoke for forcing a work holding device downwardly, means providing a series of elastic strands on the bed frame extending transversely across it, and means forming a second series 15 of elastic strands extending longitudinally of the frame over the first series.
5. A device of the class described, comprising a bed frame, means providing a series of elastic strands on the bed frame forming an 20 elastic bed, a yoke mounted on the bed frame, and a hand screw threadedly mounted upon a yoke and having a follower connected thereto by a swivel connection, said follower having a slidably, but non-rotatable connection 25 with the yoke.
6. A device of the class described, comprising a bed frame, a yoke mounted on the bed frame, two hand screws threadedly mounted upon the yoke, a follower swiveled to each 30 hand-screw, each follower having a slidably but non-rotatable connection with the yoke, and means providing a resilient bed on the bed frame beneath each follower.
7. A device of the class described, comprising a bed frame, a yoke mounted on the bed frame, two hand screws, threadedly mounted on the yoke, a follower swiveled to each hand-screw, each follower having a slidably but non-rotatable connection with the yoke, a 35 series of elastic rubber bands, positioned over the bed frame and extending in one direction, and a second series of elastic rubber bands positioned on the bed frame and extending in another direction over the first series, said 40 bands forming a resilient bed beneath each follower.
8. A device of the class described comprising a frame, a series of flat elastic strands mounted upon the frame, the side edges of 45 which are in engagement, a second series of elastic strands arranged over the first series and at an angle thereto, the side edges of the strands of the second series being in engagement with each other, and means for holding 50 work pressed against the strands so as to cause them to be stretched and exert pressure against the work.
9. A device of the class described comprising a rectangular frame, a series of elastic 55 bands stretched over the frame and extending in one direction, a second series of elastic bands stretched over the frame and extending in another direction, means providing a press over the frame, and means detachably 60
- fastening the press to the corners of the frame.
10. A device of the class described comprising a rectangular frame having outwardly extending flanges at its corners, means providing a resilient bed upon the frame, said means comprising a plurality of bands enclosing the frame, side bars having their body portions spaced from the bands and having portions fastened to the flanges, and 65 a press mounted upon the side bars.
- In testimony whereof I have signed my name to this specification.
- C. L. HUNTOON.
